UNITED STATES PATENT OFFICE.

SAMUEL ROTCHILD, OF PENDLETON, OREGON.

HARROW.

SPECIFICATION forming part of Letters Patent No. 408,930, dated August 13, 1889.

Application filed November 27, 1888. Serial No. 292,036. (No model.)

To all whom it may concern:

Be it known that I, SAMUEL ROTCHILD, of Pendleton, in the county of Umatilla and State of Oregon, have invented a new and useful Harrow, of which the following is a specification.

My invention is an improvement in harrows of the class which have fixed or stationary teeth and teeth which revolve; and the invention consists in certain novel constructions and combinations of parts, as will be herein-after described and claimed.

In the drawings, Figure 1 is a plan view of the harrow with the wheels in place. Fig. 2 is a detail view illustrating the manner of securing the fixed teeth in position. Fig. 3 is a detail view illustrating the construction of the hub of the wheel and the manner of securing the teeth therein. Fig. 4 is a detail view illustrating the protector and the manner of securing the same on the teeth of the wheel. Fig. 5 is a detail view of the wheel, and Fig. 6 is a view of a somewhat different form of harrow-frame from that shown in Fig. 1.

In the construction shown in Fig. 1 an outer frame-bar A is bent centrally between its ends at *a* to form a loop for connection of the hook or other draft-attaching device, and between the rear ends of said bar A the rear cross-bar A' extends, such bars A A' forming the outer part of the frame. Within the bars A A', I support the wheel-frames B B' B' and B² B², also the bars b' and b², which extend, respectively, between the frames B' and B² and the tooth-supporting bars C C, formed of angle-iron. Two of these bars C are arranged at and secured to the rear ends of each of the wheel-frames and form braces for such wheel-frames, as shown. Now it will be seen that I secure the front ends of the wheel-frames to the bar A, and so unite all the said frames and brace them at such end, and also provide braces for the rear end of said frames, resulting in the securing of such parts firmly and rigidly in position. I also, by means of bars A A', inclose the revolving teeth and the fixed teeth, as clearly shown.

It will be seen that the bars C at the rear ends of the wheel-frames diverge or flare outwardly in such manner as to allow the rotating teeth to pass up, even if encumbered with brush or other rubbish. At one side of the

path of the teeth of the wheel, as said teeth pass upward, I provide a rod D, which tends to slip the rubbish off the teeth, as will be understood from Fig. 1. The wheels E, as shown, are supported in bearings b at about the rear ends of their wheel-frames, and are constructed as more fully described hereinafter.

The fixed teeth F are passed through openings 1 in the horizontal flange 2 of bars C, and secured against the vertical flange 3 by staples 4, embracing teeth F, passed through flange 3, and secured by nuts, as shown, or by keys or other suitable expedients. This forms a simple and convenient fastening, and the horizontal flange of bars C aids in bracing the stationary teeth in position.

The wheel comprises the hub G, having a body part g, formed with a central opening 70 to receive the axle G', and a set-screw g', by which to secure the hub on said axle. This body part g has in one side radial grooves or chambers h, which receive the teeth H, and at the inner ends of grooves h, I provide a receptacle K for the heads or projections H' 75 on the teeth, such receptacle being preferably provided by an annular groove h'. When the teeth H have been properly fitted in the grooves h and receptacle h', I place a plate or ring H² against such spokes and against the annular portion of the hub provided with the grooves h', and secure such plate H² in position, thus holding the teeth firmly in place. By making grooves h' not quite so deep as 80 the teeth are thick the tightening of plates H² may be caused to clamp the teeth more firmly.

The protector for the outer pointed ends of the teeth consists of tire I, a ring J, and fastenings, preferably staples and pins, as shown.

The tire I is made of angle-iron, having a radial flange i and a cylindrical flange i'. A staple L has its arms held loosely in the flange i, so it may be turned up, as indicated in dotted lines, Fig. 4. The ring J fits in between the flange i' and the staple L, and against the pointed end of the tooth, a pin L' being passed through flange i', either outside of or through ring J, and connected with the staple, thus securing the staple and the ring J in position, as will be understood from Fig. 4.

In applying the protector the wheel may be

- removed from the frame by loosening the set screw and set into the tire, the latter being previously laid flat on the ground and the staples turned up, as in dotted lines, Fig. 4.
- 5 The staples may then be turned down to full-line position, the ring J be slipped in between the staples and the flange i' , and the pin L' be applied. The protector will then be properly connected with the teeth. By preference 10 the inner edge of ring J is beveled or inclined at j to correspond with the inclination of the points of the teeth.
- It will be understood that I do not wish in 15 the broad features of the invention to be confined to the particular grouping of the parts shown in Fig. 1, as it will be understood that such arrangement may be varied, and where effective work is more of an object than lightness of draft the parts may be arranged 20 as shown in Fig. 6, which would provide a wheel between every two rigid teeth. The width might be extended indefinitely to suit the purpose.
- In order to guard the wheels and protect from 25 injury any one who may accidentally fall on the harrow, I prefer to provide guard-arches M, fitted over the wheels and bolted at their ends to the framing, such arches having depending edge flanges m, as shown.
- 30 Having thus described my invention, what I claim as new, and desire to secure by Letters Patent, is—

1. The combination of the bar A, the wheel-frames connected at their forward ends with

the bar A, and the tooth-carrying bars C, secured to the rear ends of the wheel-frames and forming braces therefor, substantially as set forth. 35

2. In a harrow, the combination, substantially as described, of an outer frame bar or 40 bars, the wheel-frames arranged within said frame bar or bars and suitably secured, brace-bars extended between the forward wheel-frames and those in rear thereof and between the rear wheel-frames and the frame 45 bars, and the wheels in said wheel-frames, all substantially as and for the purposes specified.

3. In a harrow, substantially as described, the combination of the wheel-frames and bars connected with and diverging from the open 50 rear ends of said frames, whereby to present no obstruction to the upward movement of the teeth when clogged by rubbish, &c., substantially as set forth.

4. The improved protector for the toothed 55 wheels, consisting of the tire I, of angle-iron, the ring J, and fastenings, substantially as set forth.

5. The combination, with the wheel having its teeth pointed, of the angle-iron tire I, the 60 ring J, having inclined or beveled face j , the staples L, and the pins L', all substantially as set forth.

SAMUEL ROTCHILD.
